UNITED STATES PATENT OFFICE.

REGINALD S. DU BOIS, OF EAST ORANGE, NEW JERSEY.

CARBURETER-HEATER.

1,190,129.

Specification of Letters Patent.

Patented July 4, 1916.

Application filed March 20, 1916. Serial No. 85,288.

To all whom it may concern:

Be it known that I, REGINALD S. DU BOIS, a citizen of the United States, and resident of East Orange, in the county of Essex and State of New Jersey, have invented certain new and useful Improvements in Carbureter-Heaters, of which the following is a specification.

This invention relates to means for heating carbureters for gas motors.

Heretofore carbureters have been heated in various ways in order to vaporize the liquid fuel, such as gasolene, before the latter enters the cylinders of the engine whereby quicker and more complete combustion is obtained. The most common way is to put a water jacket around the carbureter and connect it with a by-pass leading from the water jacket of the motor; and it is in connection with such a system that my invention herein is illustrated. Inasmuch as the cooling water does not get heated until the motor runs, the operation of starting often becomes difficult in cold weather, and the pre-heating of the carbureter is very desirable for saving time and fuel. To accomplish such preliminary heating I provide a supplemental hot water filling device adapted to be operated manually and having the peculiar features and combinations of parts more fully described hereinafter and pointed out in the claims.

In the accompanying drawings my invention is shown applied to a common type of automobile engine which is shown in outline elevation with some of the parts in section and others cut away to disclose the interior, and in which the reference numeral 1 indicates a motor and 2 its water jacket. The latter is connected with radiator 3 by upper and lower circulation pipes 4 and 5 and a by-pass around the carbureter 6. Said by-pass comprises an upper horizontal pipe 7 and a lower vertical short pipe 8 which are commanded by valves 9 and 10 respectively, and it also includes water jackets 11 and 12 around the manifold 13 and carbureter 6 respectively. These water jackets are joined together by bolted flanges 14, all being arranged so that the water will flow around the manifold and carbureter through channel 15 and thus heat and vaporize the gasolene 16 within the chamber 6a of the carbureter. The water 28 when heated by the engine 1 flows through short pipe 4 to the radiator 3, thence downward through the

radiator and on to the right through pipe 5 back to the engine, part of the water being diverted around the carbureter and manifold as previously stated.

As the general features of the foregoing organism are old and well-known in the art no further description is necessary.

My pre-heating mechanism consists of a supplemental water filling pipe 20 which is connected with the right hand end 19 of the upper by-pass pipe 7 where it joins the top of the manifold jacket 11. This filling pipe extends upwardly to a point above the water level 21 of the radiator to prevent backflow while filling, and is provided with a funnel 22 and a valve 23 having handle 24, and it is given a slight inclination to prevent interference with the underside of the engine hood 25 which often lies in close proximity to the top of the engine.

The valve 9 is located for convenience slightly to the left of the intersecting end 19 where the lower part of the filling pipe connects, in order to intercept and prevent the ingoing hot water 27 from flowing to the left through the by-pass pipe 7 during the filling operation.

The operation of my device will now be described. The valve 23 in the top of filling pipe 20 is first opened to admit hot water and the by-pass valve 9 closed. The valve 10 below the carbureter should be left open. If hot water is now manually poured into the funnel 22 of the filling pipe 20 it will gravitate into the jacket of the manifold and carbureter because it enters at a point above the water level and forces the cold water ahead and out of the manifold and carbureter water jackets 11' and 12, and takes its place to heat the gasolene. The cold water passes out through lower pipe 8 into pipe 5 of the main system. The small amount of hot water required to fill the water jackets 11 and 12, when added to that already in the system, is insufficient to cause flooding yet ample to produce enough heat to freely vaporize the gasolene in the carbureter, also the manifold. After the filling operation is over and the motor going satisfactorily, the valve 23 at the top of the filling pipe should be closed as shown in dotted lines, and the intercepting valve 9 opened so that the general circulation may be allowed to take place.

In practising the invention I have found that my engine can be started almost in

stantly in the coldest weather, with a small quantity of hot water, and that none of the antifreezing mixture already in the water jacket need be drawn off to make room for 5 the small amount of hot water required to fill the jackets of the manifold and carbureter.

It is apparent that the foregoing construction might be varied in many ways 10 that would suggest themselves to a skilled mechanic, therefore I do not limit myself to the exact construction herein described but consider myself entitled to all variations 15 that come within the spirit and scope of my invention.

Having thus described the preferred form of my ideas, what I claim as new and desire to secure by Letters Patent is:

1. In a carbureter heater and in combination 20 with the water cooling system of a gas motor, a water jacketed carbureter, a filling pipe having its receiving end located above the water level of the water in said system, and means for preventing the diversion of 25 the ingoing water to the main system before reaching the carbureter.

2. A water jacketed carbureter connected 30 with the usual water system of a gas motor, in combination with a supplemental filling pipe having its receiving end located above the water level in said system, and an intercepting valve for shutting off the cold water from the main system to the carbureter during the filling operation.

3. A water-jacketed carbureter having a 35 supplemental water filling pipe and means

for cutting off communication between the cold water from the main system and filling pipe, said filling pipe rising to a point above the water level of the main system whereby 40 hot water, when poured into the filling pipe, will drive the cold water ahead of it and take its place around the carbureter to vaporize the gasoline therein.

4. A water-jacketed carbureter having 45 the usual intake and outlet water pipes, in combination with a supplemental water filling pipe in water communication with the water jacket, said filling pipe having a receiving end rising to a point at or above the 50 water level of the main water system and an intercepting valve for cutting off the flow to the main system during the filling operation through the supplemental pipe.

5. In a water-jacketed carbureter for gas 55 motors and in combination with the main water cooling system, a supplemental pipe adapted to receive hot water for vaporizing the liquid in the carbureter, said pipe having its upper end arranged and adapted to 60 rise above the water level of the main water system, whereby when extra water is poured into said pipe, it will be absorbed by that of the main system after having passed through the water jacket of the carbureter. 65

Signed at East Orange in the county of Essex and State of New Jersey this 7th day of March A. D. 1916.
